Primary Examiner — Antoine Duval Davis

(74) Attorney, Agent, or Firm — Stetina Brunda Garred and Brucker

(57) **CLAIM**

The ornamental design for a scan tool, as shown and described.

DESCRIPTION

FIG. 1 is a right side perspective view of the invention.

FIG. 2 is a top view of the invention;

FIG. 3 is a left side perspective view of the invention;

FIG. 4 is a front view of the invention;

FIG. 5 is a back view of the invention; and,

FIG. 6 is a bottom view of the invention.

The broken line showing of structural features is included for the purpose of illustrating non-claimed subject matter and forms no part of the claimed design.
